CLAIM

The ornamental design for an automobile bucket seat
cover or similar article, substantially as shown.

DESCRIPTION

FIG. 1 is a front perspective view of an automobile
bucket seat cover or similar article showing my design;
FIG. 2, a side view, with the opposite side being a mir-
ror image of this view;
FIG. 3, a front elevation view;
FIG. 4, a back elevation view;
FIG. 5, a top plan view; and
FIG. 6, a bottom view.
